UNITED STATES PATENT OFFICE.

MINNIE MERRYMAN, OF BALTIMORE, MARYLAND, ASSIGNOR OF ONE-HALF TO MILLIE V. GEORGE, OF BALTIMORE, MARYLAND.

OIL-SHIELD FOR SEWING-MACHINES.

SPECIFICATION forming part of Letters Patent No. 772,166, dated October 11, 1904.

Application filed May 6, 1904. Serial No. 206,604. (No model.)

To all whom it may concern:

Be it known that I, MINNIE MERRYMAN, a citizen of the United States, residing at Baltimore city, State of Maryland, have invented 5 certain new and useful Improvements in Oil-Shields for Sewing-Machines, of which the following is a specification.

My invention relates to an improvement in guards for sewing-machines, the object being 10 to provide a protection from oil or grease from coming in contact with the material while being run through the machine and at the same time provide a cheap attachment that may be applied to any sewing-machine 15 and also being easily and quickly removed; also, to provide an attachment that is attractive and will overcome the defectiveness of the present machines and commend itself to the manufacturers of the same. 20 While I have shown my invention as applied to but one style of sewing-machine, it can be made suitable for any other design machine, whether it be a machine with a straight or oval arm. 25 The necessity of my invention can be better understood by explaining that on all classes of fine materials used in the manufacture of garments, more particularly those worn by the feminine sex, such as silks and satins of 30 delicate shades, the oil which collects on the various parts of the machine comes in contact with the material while passing through, and oftentimes the material is soiled and damaged to such an extent that it becomes damaged and unfit for the purposes originally intended. 35 With these objects in view my invention consists of a guard that fits on the sewing-machine made of a suitable material, preferably 40 sheet-brass nickel-plated, having the under part perfectly smooth, while the upper edges are formed to come under the arms and sides of the machine, forming a trough to hold

whatever oil or grease which may drip from the parts that may necessarily have to be oiled 45 to prevent friction in the machine, and by so doing it necessarily protects the material while being passed under the machine and prevents it from becoming soiled or damaged.

In the accompanying drawings, Figure 1 is 50 a plan view. Fig. 2 is a side elevation of the same. Fig. 3 is an end view. Fig. 4 is a view of the device as attached to a machine.

In Fig. 1, *b* and *b'* represent the two edges of the guard turned upward. *c* represents a 55 metal clamp by which the guard is attached to the arm of the machine by means of the set-screw *e*. *f* shows a small part of the guard bent downward to rest on a part of the frame of the machine. *g* *g'* show the projections 60 resting on the upward part of the lug to secure the guard.

In Fig. 2, *d* represents a projection on the clamp *c* to rest on the frame of the machine and maintain its vertical position. The clamp 65 *c* can be attached to the guard *A* by soldering or brazing thereto, and guard *A* can be made of thin pliable metal or other suitable material.

Having fully described my invention, what 70 I claim as new, and desire to secure by Letters Patent, is—

An oil-shield for a sewing-machine attached to the overhanging arm of the machine and comprising a trough-shaped piece cut away 75 at one extremity and adapted to bear on a lug of the arm and fastened at its other extremity to the base of the arm by means of a set-screw, the trough-shaped piece conforming to the shape of the overhanging arm. 80

In testimony whereof I affix my signature in presence of two witnesses.

MINNIE MERRYMAN.
